UNITED STATES PATENT OFFICE.

TINE HEATH MACE, OF LAS CRUCES, NEW MEXICO, ASSIGNOR OF ONE-HALF TO R. P. PORTER, OF LAS CRUCES, NEW MEXICO.

SPRING-CUSHION CONSTRUCTION.

Application filed October 27, 1924. Serial No. 746,182.

To all whom it may concern:

Be it known that I, TINE HEATH MACE, a citizen of the United States, residing at Las Cruces, in the county of Dona Ana and State of New Mexico, have invented new and useful Improvements in Spring-Cushion Constructions, of which the following is a specification.

This invention relates to cushions for 10 chairs, motor vehicles and the like, and has for its object the provision of a novel cushion construction embodying a plurality of springs for giving the necessary resilience, the construction and arrangement of the 15 parts being such that the springs will be properly held and prevented from punching through the padding as so frequently occurs after prolonged use.

Another object is the provision of a seat 20 cushion construction in which all the parts are interlocked whereby displacement of any will be positively prevented even under the most adverse conditions.

An additional object is the provision of a 25 seat construction which will be simple and inexpensive, highly efficient, durable in service and a general improvement in the art.

With the above and other objects and advantages in view, the invention consists in 30 the details of construction to be hereinafter more fully described and claimed, and illustrated in the accompanying drawings, wherein:—

Figure 1 is an elevation of a seat cushion 35 constructed in accordance with my invention, a portion thereof being broken away and in section to disclose the internal construction.

Figure 2 is a cross section.

Figure 3 is a detail section showing the 40 mounting for one of the springs, and

Figure 4 is a fragmentary perspective view of one of the holding strips.

Referring more particularly to the drawings, I have shown the frame of the cushion as comprising upper and lower sets of serpentine strips 10 arranged in pairs as shown and in crossed mating relation, the strips of each pair being riveted or otherwise secured together at the points of crossing as shown at 11. The ends of the strips of each pair are out-turned as indicated at 12 for a purpose to be described. The strips of the upper series are pressed or otherwise 50 formed into channel shape in cross section

with the channel or open side extending downwardly while the strips of the lower series are correspondingly formed or shaped but arranged to extend upwardly or in the opposite direction.

The springs indicated at 13 are of the double tapered type and are located between the upper and lower series of strips, the innermost convolutions of the springs being received within the channels of the strips. By 60 this construction it is quite evident that any lateral displacement of the springs is absolutely prevented.

The frame further includes upper and lower oppositely arranged elongated metallic strips 13 which are formed at intervals with knuckles 15 within which the out-turned ends 12 of the strips 10 are engaged. Obviously, this engagement will positively 65 prevent the strips 10 of the various pairs from separating and permitting the springs 13 to slip out.

The cushion further includes side walls 16 of flexible material disposed outwardly of the metallic strips 13 and secured thereto 70 by riveting or otherwise as indicated at 17, it being preferable to provide reinforcing strips 18 of metal or even of flexible material outwardly of the side walls 16 at the points where the rivets or other securing 75 devices pass through, the purpose being to prevent ripping and make the structure strong. The side walls 16 may be prolonged and formed integrally with the seat portion 19, as shown in Figure 2 or separate pieces might be secured together, this detail being immaterial. The numeral 20 represents the usual padding which is interposed between the cover or seat 19 and the 80 uppermost series of strips 10. Logically it is well within the scope of the invention to provide a seat 21 of flexible material to cover the upper series of strips 10 and the upper ends of the springs to further reduce 85 any likelihood of displacement of the padding or punching through of the springs and their securing strips.

From the foregoing description and a study of the drawings, it will be readily apparent that I have thus provided a very simple and inexpensive seat construction in which all the parts are absolutely locked together so that displacement in any direction will be positively prevented. It is obvious that a seat constructed in accordance 105 110

with this invention will possess far greater durability than those of the ordinary type and they should have a long and satisfactory life.

5 While I have shown and described the preferred embodiment of the invention, it should be understood that I reserve the right to make such changes in the form, construction and arrangement of parts as 10 will not depart from the spirit of the invention or the scope of the subjoined claims.

Having thus described the invention, I claim:—

1. In a seat cushion construction involving a plurality of springs, strips arranged in pairs with the strips of each pair passing to the left of one spring and to the right of the adjoining spring and secured together at their points of crossing, the strips being 20 channel shaped in cross section and conformingly receiving the endmost convolutions of the springs, and anchoring means for the ends of the strips.

2. In a seat cushion construction involving a plurality of springs, strips arranged in pairs with the strips of each pair passing to one side of one spring and the other side of the adjacent spring and secured together at their points of crossing, the strips being

30 channel shaped in cross section and conformingly receiving the endmost convolutions of the springs, and anchoring means for the ends of the strips, said anchoring means comprising elongated metallic strips having knuckles thereon receiving the ends 35 of the first named strips.

3. In a seat cushion construction involving a plurality of springs, strips arranged in pairs with the strips of each pair crossing at intervals and secured together at their 40 points of crossing, the strips being channel shaped in cross section and conformingly receiving the endmost convolutions of the springs, each strip passing to one side of one spring and to the other side of the next 45 spring, and anchoring means for the ends of the strips, said anchoring means comprising elongated metallic strips having knuckles thereon receiving the ends of the first named strips, flexible side walls secured to said last named strips, a cover formed as the continuation of said side walls and confining the seat proper, and a 50 padding located between the first named strips and said cover.

In testimony whereof I affix my signature.

TINE HEATH MACE.
